UNITED STATES PATENT OFFICE.

MARGARET E. TORREY, OF CLEVELAND, OHIO.

ADVERTISING DEVICE.

1,238,960.

Specification of Letters Patent.

Patented Sept. 4, 1917.

Application filed August 17, 1915. Serial No. 45,911.

To all whom it may concern:

Be it known that I, MARGARET E. TORREY, a citizen of the United States, residing at Cleveland, in the county of Cuyahoga and State of Ohio, have invented new and useful Improvements in Advertising Devices, of which the following is a specification.

This invention relates to a device for attractively exposing a large number of advertising signs, that can be viewed from all directions.

The object of this invention is to attract the attention of the public whereby during the day or night, they may be informed as to the nature of various wares, a large number of advertisements being displayed at a time as they pause momentarily and in such manner that a minimum of effort is required to operate the machine.

20 In the accompanying drawings:

Figure 1 is a sectional elevation of the device taken on line 1—1, Fig. 2. Figs. 2, 3 and 4 are horizontal sections taken on the correspondingly numbered lines in Fig. 1.

25 Fig. 5 is a fragmentary sectional perspective view, on an enlarged scale, of the device that locks the rotary frame during its idle period the section being taken approximately on line 5—5, Fig. 1. Fig. 6 is a horizontal section, on an enlarged scale, taken on line 6—6, Fig. 1.

Similar characters of reference indicate corresponding parts throughout the several views.

35 1 represents a horizontal, circular plate or base which forms the main frame of the device and upon which is rotatably mounted the turret frame which carries the advertisements. This base is provided at its center with a vertical bearing 2 and near its outer rim with an upwardly projecting annular flange or wall 3 which protects the base and the lower parts of the apparatus from the weather.

40 45 Journalized in the base bearing 2 is a vertical rotating axle or mast 4 which passes below the lower surface of the base and is provided at its lower end with a screw nut 5 which normally, freely clears the lower surface of the base but is caused to engage with the same should high winds cause excessive tipping of the axle or mast, thereby limiting the tipping of the same. The latter near its lower end is pinned to a horizontal spider-shaped plate or platform 6

provided with eight outwardly and laterally projecting sweeps or arms 7 the outer ends of which are provided with the vertical anti-friction rollers 8 whose axes all pass through the axis of the mast. This 60 permits the mast and the platform with its load to freely rotate horizontally about the mast as a center.

The mast is firmly braced to the platform by four inclined mast braces 9.

To the upper end of the mast is secured an upper horizontal disk or plate 9 provided at its center with a vertical hole 10 through which the mast passes. The upper end of said mast is provided with a screw nut 11 70 engaging with the upper side of the top plate 9. On its underside the top plate is connected with the mast by braces 12. The mast, lower and upper plates and the braces together form the main elements of the rotary turret or revolving frame of the advertising device. If desired, a dome or canopy 13 preferably in the form of a bell may be arranged above the top plate, and this is in turn surmounted by a suitable ornament 14 75 such as an eagle, as shown in Fig. 1.

Secured to the upper surface of the base is a gear wheel 15 whose axis is concentric with the mast. The teeth of this gear wheel are intermittently engaged, as best shown in Fig. 4, with a mutilated gear wheel 16 which has only one short row of teeth 17 on its outer rim and which is provided with an upwardly extending vertical spindle 18 that is journaled in the bearing 19 of the lower 90 platform. To the upper end of this spindle is secured a worm wheel 20, thus causing said worm wheel and the mutilated gear wheel to turn together on a vertical axis. Mounted on the upper surface of the platform is a shaft or other constant speed electric motor 21, on whose shaft is keyed a worm 22 which meshes with the worm wheel 20. Thus, as this constant speed motion is transmitted to the mutilated gear wheel below the platform, the latter is caused to intermittently turn through a predetermined portion of a revolution and then rest idly for a period. The power may be applied to the mast from an external source where conditions so warrant but the device as shown is usually preferable in that it is self contained.

In the upper surface of the base and embedded in rubber or other electric insulat-

ing material are two current conducting rings 23, 23 which are concentric with the mast and which have their upper faces exposed. These rings are electrically connected with the external electric current or power line. Secured to the lower surface of the platform and properly insulated therefrom are two downwardly bent spring conductor brushes 24 which maintain contact with the rings 23 as said platform rotates on the base. These brushes are electrically connected with the motor 21, so that, when the current is turned on, the turret automatically starts its intermittent partial rotations.

15 Mounted in the turret frame between the upper and lower plates are eight vertical drums or cylinders 25 preferably triangular in cross section which rotate on vertical axes. Each of these drums or cylinders preferably comprises top and bottom heads 26, 27 of triangular form, three upright bars or mullions 28 connecting corresponding corners of these heads and panes or panels 29 of transparent or translucent material secured in the 25 rectangular spaces between said bars and the edges of the upper and lower heads. The signs or advertisements of any desired character are placed on these panels or panes in any suitable manner so that the same are 30 visible either during daytime as well as in the night upon illuminating the interior of the cylinder.

35 The upper pivots of the cylinders consist of eight large vertical pivot tubes or hollow journals 29¹ driven tightly into the upper frame plate and passing through vertical bearings 30 in the upper heads of the cylinders. To the lower end of each cylinder is secured a horizontal triangular block 31 which has its center in the axis of the cylinder and whose lower flat surface bears 40 against the upper face of the lower plate or platform 6. A vertical spindle 32 is screwed into the lower central part of this block and passes downwardly through a suitable bearing 33 in the adjacent arm of the lower plate or platform, and to the lower end of this spindle is secured a pinion 34. The pivots 32 and 29¹ of each cylinder are axially in 45 line.

50 A horizontal, mutilated gear rim or ring 36 is secured to the upper surface of the base concentric with the mast, as best shown in Fig. 4. This gear rim is provided on its outer edge with eight geometrically arranged sets or groups of gear teeth 35 which alternate with blank spaces on the periphery of this gear rim. Although the number of cylinders may be varied, eight are shown 55 in the drawings, and these are divided into two sets of four each, the members of one set alternating with the members of the other set for purposes which will presently appear. As the turret frame rotates in the direction indicated by the arrow, one set of

four cylinders is first caused to move through a third of a revolution and then, on further travel of the turret frame, the other set of four cylinders is turned, the first set meanwhile being held stationary relatively to the turret frame.

This is accomplished by so arranging the groups of gear teeth on the gear rim that successive pairs of groups of these teeth are arranged comparatively near each other but remote from the pairs on opposite sides of the same, as shown in Fig. 4. By this means, as the turret turns forward one step, the cylinders of one set are turned one-third of a rotation during the first half of this step and then the other set of cylinders are turned one-third of a rotation during the last half of this step, thereby permitting of placing the several cylinders close together without interference and still enabling the same to be turned about their individual axes for displaying the advertisements on their several panels successively.

45 Each of the cylinders is held against rotary displacement when the same is not to be turned by a group of gear teeth 35 on the gear rim, this being preferably effected by a spring 37 mounted on the lower platform and bearing laterally and radially against adjacent flat faces of the triangular block 31 on the lower head of the cylinder. Thus, during an eighth rotation of the frame, all the cylinder pinions, and hence the cylinders, are turned a third revolution relatively to the frame. Then the frame pauses a moment while the advertisements are being scanned, said frame being retained stationary in the meantime by means of a bent spring 38 secured to the upper surface of the base and successively engaging the lower 50 portions of the lower platform arms 7 as the frame rotates.

55 It will be clear from the foregoing description that the frame advances upon each actuation by one-eighth of a revolution, so that the sets of teeth 35 which are close to and upon each side of alternate pinions 34 are advanced into a similar relation with respect to the next alternate pinions.

60 Electric wires pass up from the brushes 24 to the upper surface of the upper turret plate and are secured to a plurality of wires depending through the upper cylinder pivot tubes 29¹ and to the lower ends of these wires are secured a number of electric light bulbs 39. In large devices, a single light provided with suitable reflectors and placed up over the mast is practical but the device shown gives a very even illumination and permits of changing the sizes of the bulbs when a 65 different set of signs of different opaqueness is to be placed in any cylinder. By making the upper pivots of the sign cylinders hollow the same not only form a convenient means for introducing the lights and

wires into the cylinders but they also serve as flues to permit the air to escape from the interior of the cylinders and thus avoid undue heating of the same.

5 I claim as my invention:

1. An advertising device comprising a base, a frame rotating on said base, sign cylinders rotating in said frame, pinions mounted on the cylinders, a mutilated gear rim mounted on the base and intermittently and successively engaged first by the pinions of some of said cylinders and then by the pinions of other cylinders, and means for intermittently turning said frame.
- 15 2. An advertising device comprising a base, a frame rotating on said base, sign cylinders rotating in said frame, pinions mounted on the cylinders, a mutilated gear rim mounted on the base and intermittently and successively engaged first by the pinions of some of said cylinders and then by the pinions of other cylinders, translucent panes adapted to bear advertising signs arranged in the cylinder walls, means for illuminating

the interior of the cylinders, and means for 25 rotating the frame.

3. An advertising device comprising a base, a mast journaled on the base, a moving platform supported by said base and secured to the mast, an upper plate arranged 30 above said platform and secured to the mast, inclined braces connecting said plate and platform with said mast, means for supporting advertising signs between said plate and platform, and means for moving said platform, plate and mast and the parts mounted thereon.

4. An advertising device comprising a rotatable frame, cylinders rotatably mounted in said frame and adapted to carry advertising signs, means for successively moving the frame through a portion of a rotation, and means for automatically turning one half of the number of cylinders on the frame through a partial rotation while the frame 45 is moving through a partial rotation from one position to another.

MARGARET E. TORREY.
